HANK OR SKEIN-WINDING MECHANISM

Bertram J. Goldsmith, Allentown, Pa.

Application October 8, 1930. Serial No. 487,109

12 Claims. (Cl. 242—53)

This invention relates to improvements in winding mechanisms, and more particularly it pertains to a novel hank or skein and a mechanism for forming the same. In its present embodiment, the invention is illustrated in a machine for forming relatively small hanks or skeins of ribbon, but it will be understood that it may also be embodied in machines for operating upon materials other than ribbon.

10 At present it is a common practice to form relatively small hanks or skeins of ribbon upon a power driven head, strip the formed hank or skein from the head, on which it is formed, sever it with a pair of hand shears from the longer strip of ribbon from which it is formed, after which the free end of the relatively long strip is threaded again into the head, and the afore-described cycle of operations repeated.

These machines are generally attended by female operatives, and the severing and re-threading operations are carried out by hand. In spite of the fact that operatives become highly efficient in the operation of such machines, the severing of the formed hank or skein, and the rethreading of the head are tedious and time consuming operations as at present performed, and the volume of work which an operative can produce upon such machines is necessarily limited by her efficiency in severing the formed hank or skein from the strip of material from which it is formed, and the rethreading of the material in the head.

Inasmuch as ribbon is formed into relatively small hanks or skeins to meet the demands of a relatively low price market, it is highly desirable that they be produced as cheaply as possible, and the device of the present invention aims to reduce the cost of manufacture of relatively short lengths of ribbon in hank or skein form, by materially increasing the output quantity or volume of hank or skein forming machines.

It is one of the objects of the present invention to provide a novel construction whereby the formed hank or skein may be severed from the strip of material from which it is formed without employing separate hand shears or similar means.

It is another object of the invention to improve the construction of the strip holding means, and thereby greatly facilitate the threading or rethreading of the machine.

50 It is still another object of the invention to provide a novel mechanism whereby the severing of the finished hank or skein from the strip from which it is formed is performed after the strip has been re-threaded into the winding head, thus greatly facilitating the re-threading of the

head, and insuring a firm gripping of the free end of the strip from which the hank or skein is formed.

Still another object of the invention resides in the provision of a novel means whereby the preparation of the mechanism for rethreading, automatically performs the hank or skein stripping operation.

Other objects of the invention will appear as the nature of the invention is better understood, and to this end, reference will be had to the following description and the accompanying drawings, wherein:

Fig. 1 is a view in front elevation of a hank or skein forming mechanism illustrating the same in the initial step of forming the hank or skein.

Fig. 2 is a similar view showing the formed hank or skein.

Fig. 3 is a similar view illustrating the re-threading operation.

Fig. 4 is a view in elevation taken in the direction of the arrow X in Figure 1.

Fig. 5 is a similar view in detail, and on an enlarged scale, illustrating the strip clamping and severing means in open position.

Fig. 6 is an enlarged detail view in elevation, and partly in section taken in the direction of the arrow Y, in Figure 4.

Fig. 7 is a detail sectional view on an enlarged scale, taken on the line 7—7 of Figure 6.

Fig. 8 is a detail sectional view taken on the line 8—8 of Figure 6; and

Fig. 9 is a detail sectional view on an enlarged scale taken on the line 9—9 of Figure 6.

In the present embodiment of the invention, the hank or skein-forming head consists of a relatively narrow member 10, carried by a shaft 11, being connected thereto by a suitable hub or like member 12. The shaft 11 is driven in any suitable manner not herein illustrated, and may be mounted for rotation in a bearing 13 which in turn may be rigidly supported in any desired manner.

The member 10 carries two winding posts 14 and 15, they being mounted adjacent the ends of said member 10, as best illustrated in Figures 1 to 3 inclusive of the drawings. As best illustrated in Figure 4, the winding post 14 is adjustably mounted in an elongated slot 15' in the member 10 by means of a nut 16 threaded upon the winding post 14 and adapted to clamp the member 10 between itself and a shoulder 17 presented by an enlarged portion 18 of the winding post.

The opposite end of the member 10 may be twisted as at 19 to present a flat face 20 substantially at right angles to the main body portion of the member 10, and as best illustrated in Figure 6, the winding post 15 is mounted as at 21, on this flat face 20, for pivotal movement about a stud or the like 22 which passes through a lug or projection 23 extending from the edge of the winding post 15. For rocking the winding post 15 about its pivotal point 21, a handle 24 may be provided, and a spring 25 secured at one of its ends to the winding post 15, as at 26 and at its other end to a stationary point 27, serves normally to maintain the winding post 15 in a position in which it is at right angles to the longitudinal axis of the member 10, as illustrated in Figures 1 and 2.

The winding post 15 differs in construction from the winding post 14, since it is this winding post 15 which forms the holding means of the ribbon strip from which the hank or skein is formed, and it also includes the severing means by which the formed hank or skein is cut or severed from the strip.

The specific construction of this winding post 15 is best illustrated in Figures 6 and 7 and, by reference to said figures, it will be seen that the main body portion of the winding post 15 is cut out as at 33. Pivotaly mounted in this cut out portion 33, as at 34, there is a clamping jaw or member 35 reduced as at 36, to receive the main body portion of said winding post 15. The opposite end of this clamp is formed with a nose 37 which is adapted to ride over a cam face 38 upon the rear of a plate 39 secured, as at 40, to the member 10.

By this construction, as the winding post 15 is rocked about its pivotal point 21 by its handle 24, the clamp 35, by reason of engagement of its nose 37 with the cam face 38 will be rocked about its pivotal point 34, to the position illustrated in broken lines in Figure 7. To insure engagement of the nose 37 of the clamp 35 with the cam face 38, a spring 44 is interposed between the clamp 35 and the right angular extension 45 of a bracket 46 secured as at 47 to the winding post 15.

In addition to forming a clamp for the ribbon strip the member 35 acts in conjunction with an edge 50 undercut as at 51 to sever the formed hank or skein from the strip from which it is formed, and this severing action is completed simultaneously with the clamping operation in a manner hereinafter described.

The device operates in the following manner: The ribbon strip from which the hank or skein is formed is designated 55, and it is supplied from a suitable roll, spool or in any other desired manner over a suitable guide 60. This guide 60, preferably consists of a circular member formed with a groove 61, and a spring tension finger 62 overlies said groove as shown in Figures 1 to 3. Passing through the groove 61 and arranged diametrically opposite to the ribbon strip 55, there is a strip 63 of paper, preferably wider than said ribbon strip, which not only forms a protection for the latter strip, but also provides a support for the various loops of the hank or skein between which the paper strip is interposed, whereby said loops will have a certain amount of rigidity imparted thereto and be better maintained in aligned positions relative to each other.

In Figure 1, the ribbon strip 55 and the paper strip 63 are shown as attached to the winding post 15 in position to start the formation of the

hank or skein. This attachment of the strips 55 and 63 to the winding post 15 is accomplished by grasping the handle portion 24, and rocking the winding post 15 around its pivotal point 21. This movement of the winding post 15 causes the cam face 38 to move the clamp 35 to the broken line position in Figure 7, and permits of the insertion of the ends of the two strips between the clamp 35 and the co-operating part of the winding post 15. If now the handle 24 be released, the parts return to the position in which they are shown in Figure 1 and the hank or skein forming operation is ready to start.

The head is now rotated to form the desired number of loops about the winding pins 14 and 15 after which a clip 65 of stiff cardboard, metal or other suitable material is passed around the body portion of the hank or skein intermediate said pins to maintain the formation illustrated in Figure 3.

After the hank or skein has been formed, it is stripped from the head in the following manner. The operative grips, with one hand, the strips 55 and 63, and with the other hand, grasps the handle 24 and rocks the winding pin 15 around its pivotal point. This action moves the clamp 35 to release the ends of said strips which were gripped before the coils of the hank were formed, and also moves the winding post 15 from within one of the loops of the hank or skein, leaving the same hanging upon the winding post 14.

The handle 24 is maintained in its rocked position until the uncut portions of the strips which will form the outer end of the hank are again passed between the clamp 35 and the adjacent portion of the winding post 15, after which the handle 24 is released so as to return to normal position, thereby clamping the two strips 55 and 63 to said winding post.

As the clamp 35 moves to clamping position 115 its edge 65', in passing by the undercut edge 50, produces a shearing action which severs the formed hank or skein from the strips simultaneously with the clamping of the free ends of the latter produced by the cutting operation, after 120 which the hank or skein is removed from the winding pin 14 and the aforementioned cycle of operation completed to form another hank or skein. To insure a complete shearing action, the edge 65 of the clamp 35 is maintained resiliently in engagement with the under cut edge 50 of the winding pin 15 by a flat spring 70 mounted in the cut out portion 33 of the winding post 15, and this spring has its free end 71 engaging the clamp 35 as best shown in Figure 6.

By threading the winding post 15 before the hank or skein is severed from the strips from which it is formed, the threading operation is greatly facilitated since the operation is more easily carried out in this manner than in the heretofore commonly employed manner of threading in the free end of a strip. By making the hank or skein severing operation simultaneous with the clamping operation, the necessity of employing separate hand shears or the like is obviated, and the hank or skein severing operation is greatly facilitated.

From the foregoing, it will be apparent that the present invention provides a novel mechanism by which the formation of hanks or skeins of ribbon may be carried out with greater facility than is possible with such mechanisms as heretofore constructed, and that the device of the present invention is very simple in construction, and highly efficient for the purpose intended.

- Having thus described the invention, what is claimed is:
1. A hank or skein forming mechanism including a rotary head, a plurality of winding posts carried by said head and around which the hank or skein is formed, means carried by one of said winding posts for gripping the free end of a strip of material from which the hank or skein is to be formed, means for moving the last-mentioned winding post to hank or skein releasing position, and means actuated during the movement of said winding post for operating said strip gripping means to release the strip. 80
  2. A hank or skein forming mechanism comprising a rotary head, a plurality of winding pins, and means carried by one of said pins for gripping a strip of material from which a hank or skein is formed and for severing a formed hank or skein from the strip, the last mentioned means comprising a clamping bar pivotally mounted on one of said winding pins. 85
  3. A hank or skein forming mechanism including a head, winding members carried thereby about which two strips of material are wound in superimposed relation to form the hank or skein, severing means for said strips associated with one of said winding members, and a guide engaged on opposite sides thereof by said strips before they are wound on said winding members. 90
  4. A hank or skein forming mechanism including a rotary head, a plurality of winding posts carried by said head and around which the hank or skein is formed, means carried by one of said winding posts for gripping the free end of a strip of material from which the hank or skein is to be formed, means for moving the last-mentioned winding post to hank or skein releasing position, means actuated during the movement of said winding post for operating said strip gripping means to release the strip, and means thereafter operable to sever the formed hank or skein from said strip. 100
  5. A hank or skein forming mechanism including a pair of elements upon which a hank is wound, one of said elements being movable relative to the other to a hank-releasing position, means to rotate said elements about a common axis to form said hank, gripping members for a strip of material of which the hank is formed associated with one of said winding elements, and means operated by the movement of the first-named winding element to its hank releasing position to cause said gripping members to release said strip. 105
  6. A hank or skein forming mechanism including a pair of elements upon which a hank is wound, one of said elements being movable relative to the other to a hank-releasing position, means to rotate said elements about a common axis to form said hank, gripping members for a strip of material of which the hank is formed associated with one of said winding elements, and means operated by the movement of the first-named winding element to its hank releasing position to cause said gripping members to release said strip, said gripping members having means to sever a formed hank from said strip upon the return of said members to gripping position. 110
  7. A hank or skein forming mechanism includ- 115
- ing a pair of elements upon which a hank is wound, one of said elements being movable relative to the other to a hank-releasing position, means on said movable element to grip a strip of material from which a hank is formed and to cut said strip after the formation of a hank, and means to move said gripping means to strip-releasing position when said movable element is moved to hank-releasing position, said means being also effective to cause said gripping means to cut said strip upon restoration of said movable element to its hank-winding position. 120
8. A hank or skein forming mechanism includ- 125
- ing a pair of elements upon which a hank is wound, one of said elements being movable relative to the other to a hank-releasing position, said movable element comprising a post, a clamping jaw pivoted to said post, a support upon which said post is pivoted and having a cam engaged by said clamping jaw to move the latter to operative and inoperative positions relative to a strip of material between said jaw and post when the latter is moved about its pivot. 130
9. A hank or skein forming mechanism comprising a rotary shaft, a bar secured to said shaft, winding posts at opposite ends of said bar, one of said posts being pivoted intermediate its ends to said bar for movements to hank-winding and releasing positions and including relatively movable members operable to grip and to sever a strip of material therebetween, and means on said bar for controlling the operations of said movable members. 135
10. A hank or skein forming mechanism comprising a rotary shaft, a bar secured to said shaft, winding posts at opposite ends of said bar, one of said posts being pivoted to said bar for movement relative to the other post and having an operating handle at one end and a pair of relatively movable members at its other end cooperating to grip and to sever a strip of material therebetween, and means on said bar for controlling the operations of said movable members. 140
11. A hank or skein forming mechanism comprising a rotary shaft, a bar secured to said shaft, winding posts at opposite ends of said bar, one of said posts being pivoted to said bar and including relatively movable members one of which is partially recessed and pivoted within the other member, said members having cooperating portions for gripping therebetween a strip of material and for severing said strip, and means to control the gripping and severing actions of said portions during movements of said post about its pivot. 145
12. A hank or skein forming mechanism comprising a rotary shaft, a bar secured to said shaft, winding posts at opposite ends of said bar, one of said posts being pivoted to said bar and including relatively movable members one of which is partially recessed and pivoted within the other member, said members having cooperating portions for gripping therebetween a strip of material and for severing said strip, and a cam on said bar engaging said recessed member to control the gripping and severing actions of said cooperating portions during movements of said post about its pivot. 150
